DESIGN FOR A COMBINED BAGGAGE RACK AND LIGHTING FIXTURE OR SIMILAR AR- TICLE

Sterling B. McDonald, Itasca, Ill., assignor to The
Adlake Company, a corporation of Illinois

Application August 15, 1936, Serial No. 64,422

Term of patent 14 years

To all whom it may concern:

Be it known that I, Sterling B. McDonald, a citizen of the United States of America, and a resident of Itasca, county of Du Page, and State of Illinois, have invented a new, original, and ornamental Design for a Combined Baggage Rack and Lighting Fixture, or Similar Article, of which the following is a specification, reference being had to the accompanying drawing, forming a part thereof, wherein

Fig. 1 is a perspective view of a combined baggage rack and lighting fixture embodying my new design;

Fig. 2 is a fragmentary bottom plan view of the combined baggage rack and lighting fixture with an intermediate portion broken away; and

Fig. 3 is a sectional view on the line 3—3 of Fig. 2.

I claim:

The ornamental design for a combined baggage rack and lighting fixture, or similar article, substantially as shown.

STERLING B. McDONALD.
